E. C. Bacon.

Pitman.

No 85,266.

Patented Dec. 29. 1868.

EARLE C. BACON, OF NEW YORK, N. Y.

Letters Patent No. 85,266, dated. December 29, 1868.

IMPROVEMENT IN PITMAN.

The Schedule referred to in these Letters Patent and making part of the same.

To all whom it may concern:

Be it known that I, EARLE C. BACON, of the city, county, and State of New York, have invented a new and useful Improvement in the Tightening of the Bearing-Brasses to Pitman and Connecting-Rods, &c.; and that the following description, taken in connection with the accompanying drawings, hereinafter referred to, forms a full and exact specification of the same, wherein I have set forth the nature and principles of my said improvement, by which my invention may be distinguished from all others of a similar class, together with such parts as I claim, and desire to have secured to me by Letters Patent.

The principal object of the present invention is to enable the two sets of bearing-brasses of pitman and connecting-rods, &c., which are located at or near each end thereof, to be tightened about their respective journals, bearings, or shafts, by means of one gib and key, or one set of wedges, ordinarily employed for such purpose, thus dispensing with a gib and key, and a strap at one end of the pitman-rod, &c.; and for this purpose,

The invention consists in extending through the pitman-rod, from the gib and key to the bearing-brasses, at the opposite end of the pitman-rod to that at which the said gib and key and strap are located, a rod, and in so combining such rod with said bearing-brasses, and the key and gib, that thereby, when the key is driven, not only will the bearing-brasses at one end, through the strap, be tightened about their journal-bearing or shaft, as ordinarily, but also the bearing-brasses at the other end about their journal, &c., as is obvious.

In the accompanying plate of drawings my invention is illustrated,

Figure 1 being a side and exterior view of a pitman or connecting-rod from end to end, and

Figure 2, a central longitudinal section, taken in the plane of the line $x-x$, fig. 1.

A, in the drawings, represents a pitman or connecting-rod, and B, a strap placed around one end of the same.

In this strap B, one set of the ordinary bearing-brasses C is placed, and there confined in the usual manner.

D, a gib, and E, a key, both arranged in the strap B, and passing from one side to the other of the same, as ordinarily, so that by driving the key in or out, the brasses C will be tightened or loosened, as the case may be, about their journal-bearing or shaft, the said key and gib acting through the strap B thereon, in the ordinary manner.

F, a rod, extending from gib D through the pitman-rod A, that is made hollow therefor, to a set of bearing-brasses, H, that are located at the opposite end, I, of the pitman-rod A to that having the strap B encircling it.

With a rod, F, extended from a gib and key to a set of bearing-brasses, as above described, it is plainly obvious that as such key is driven in or out, said bearing-brasses will be consequently tightened or loosened, as the case may be, about their journal-bearing or shaft, such key at the same time acting through the strap to tighten or loosen the set of bearing-brasses carried by it about their journal, &c.

By my invention, a gib, a key, and a strap are dispensed with, and consequently the necessary fitting up of the same—an advantage of much importance.

To prevent the end of the rod F from cutting into the surface M of the bearing-brass whereon it acts, a steel or other suitable plate, N, is interposed between the two.

Although I have herein particularly described the rod F, for tightening one set of brasses, as operated by the gib D and key E, which I think the most desirable and practicable for obvious reasons, still I do not wish to limit myself to any one particular mode of forcing the rod, nor do I intend to limit myself to the fact that the two sets of brasses are tightened by one and the same gib and key, that is, simultaneously, but I deem such arrangement and construction preferable.

Having thus described my improvement, I shall state my claims, as follows:

1. The rod F, or its equivalent, in combination with the bearing-brass, to a pitman and connecting-rod, &c., when the rod F, or its equivalents, is arranged within the pitman or connecting-rod, &c., for operation upon one set of the bearing-brasses thereof, substantially as and for the purpose described.

2. The rod F, or its equivalent, in combination with the bearing-brasses to a pitman and connecting-rod, &c., and a gib, key, and strap, or their respective equivalents, when all arranged together for operation, substantially as and for the purpose described.

3. The plate N, interposed between bearing-brasses and rod F, substantially as described, for the purpose specified.

EARLE C. BACON.
